UNITED STATES PATENT OFFICE

2,631,879

DOOR HANDLE ASSEMBLY

Burnie J. Craig, Los Angeles County, Calif.

Original application May 3, 1944, Serial No. 533,958, now Patent No. 2,450,372, dated September 28, 1948. Divided and this application June 25, 1948, Serial No. 35,172

11 Claims. (Cl. 292—177)

1

The general object of the invention is to provide a novel door handle assembly.

A further object of the invention is to provide a novel inside door handle and catch release member.

Another object of the invention is to provide a novel outside handle and catch release member.

Another object of the invention is to provide a novel door handle mounting means.

A further object of the invention is to provide a novel catch release member which is adapted to be mounted on a support such as a handle.

A further object of the invention is to provide a novel means for mounting a latch operating member on a door handle.

An additional object of the invention is to provide a novel anatomically correct combined grip and latch releasing member for a vehicle door.

A further object of the invention is to provide a novel handle including means permitting it to be angularly adjusted.

Other objects and advantages of the invention will be apparent from the following description taken in connection with the accompanying drawings, wherein:

Fig. 1 is an isometric view with parts broken away, showing the outside release member and its mountings;

Fig. 2 is an isometric view, with parts broken away, showing the manner in which the outside release member is assembled;

Fig. 3 is an isometric view showing the outside push release member;

Fig. 4 is an isometric view showing the clip for supporting the outside release member;

Fig. 5 is a fragmentary top plan view, with parts broken away, showing the outside handle;

Fig. 6 is a fragmentary central sectional view through the handle;

Fig. 7 is a view taken on line 7—7, Fig. 6;

Fig. 8 is a view taken on line 8—8, Fig. 7;

Fig. 9 is a section taken on line 9—9, Fig. 7;

Fig. 10 is a central sectional view showing the inside release member;

Fig. 11 is a top plan view showing the inside release member;

Fig. 12 is an extended view showing the elements of the inside release member;

Fig. 13 is a view similar to Fig. 10 showing the handle prior to assembly, and

Fig. 14 is an isometric view showing the inside release rocker arm.

This application is a division of application Serial No. 533,958, filed May 3, 1944, now Patent No. 2,450,372, granted September 28, 1948.

In the accompanying drawings the invention is shown as embodied in an automotive vehicle door latch handle assembly which is indicated generally at 105. A latch is provided for the front doors 11 and rear doors 12 of a four-door sedan, although the invention is adapted for use with other types of vehicles.

2

The handle assembly 105 is adapted for use with a latch which includes a base plate 16 having a bolt 30 slideable thereon. The bolt includes a pivoted operating member 47 which may be rocked by movement of an actuating member to be later described. The bolt also includes a rotatable sleeve 60 having an operating member 82 thereon adapted to be rocked by an actuating member to be later described. The construction is such that when either the operating member 47 or the operating member 82 is rocked, the latch bolt will be released.

Details of the construction and operation of the latch and bolt and the means whereby either the operating member 47 or the operating member 82 is caused to release the bolt are described in detail in Patent No. 2,450,372, mentioned above. The present door handle assembly construction may be used with many types of door latches and the particular type of bolt and operating member disclosed herein merely describes one of many types which may be employed.

The handle assembly includes an inside supporting plate 75 having a base 76. A threaded collar 79 on the base is aligned with the operating member 82. On the inner face of the door panel 84 a pair of handle support plates 85 and 86 are held in place by spot welding as at 87. These plates 85 and 86 are spaced apart to provide a slot 88. The plates are notched at 89 to receive the bolt 30. The plates 85 and 86 are provided with rails 91 and 92 respectively (see Fig. 1) which overhang the adjacent parts of the front door panel to form slots 93.

The handle assembly includes a body 106 shown as made from a single piece of material and including a grip portion 107 and an attaching portion 108. The forward end of the attached portion 108 has bevelled sides 109.

The walls of the plates 85 and 86 converge as shown at 110, Fig. 7, to correspond with the bevel 109 on the handle securing portion. The portion of the handle adjacent to the bevelled portion 109 is of substantially the same thickness as the depth of the slots 93 defined by the rail members 91 and 92 and thus the handle portion may be inserted beneath these members 91 and 92 with the bevelled end 109 providing a tight fit. A screw 111 (Fig. 7) is then inserted through a hole 112 in the end panel of the door and into a threaded hole 113 in the handle portion 108. Thus a single screw may serve to hold the handle in operative position.

The handle includes a U-shaped housing portion 114 which fits into the adjacent portions 107 and 108 of the handle and may be welded in place. The inner end of the portion 114 is open. The handle includes a slot 115 arranged in the portions 107 and 108.

A bolt actuating member, indicated generally at 116 (Fig. 2), includes a body portion 117 which includes spaced wings 118 and a forwardly pro-

jecting portion 119 having an offset end portion 120 which terminates in a reduced tip 121. The portion 108 of the handle is slotted as at 122 and beyond the slot is provided with an end flange or tongue 123. The offset portion 120 provides a shoulder 128 which limits outward movement of the member 116 by engaging the outer end wall of the slot 122. The wings 118 are pivoted to the sides 124 of a push member 125 (Figs. 2 and 3) by a pin 126 which fits into holes 127 in the member 125. The push member 125 is of a size to slide in the slot 115 and normally projects as shown in Fig. 1 so that it is accessible for actuation.

The push member 125 has a hole 128 which receives a pin 129. This pin 129 is mounted in holes 129 in a U-shaped member 130 (see Fig. 4). The U-shaped member is cut away as at 131 so that it may slide into the housing portion 114 of the handle. The outer end 132 of the member 130 when assembled is flush with the end 133 of the housing, so that when the housing is in position upon the door the U-shaped member is held in place. A spring 134, Fig. 6, surrounds the pin 129 and engages the portion 117 and the push member 125 to urge the latter to projecting position.

When the member 125 is depressed as by the thumb sweeping thereover the tip 121 on the body portion 117 will enter the slot 46 of the bolt and will engage the operating member 47 to actuate the latter to release the latch device. A modified door handle assembly is indicated generally at 140 in Figs. 10 and 11. As shown the assembly 140 includes a grip portion 141 and a housing portion 142 which has a hole 143 through which an elongated finger tip release push member 144 protrudes. The member 144 is shown as mounted in a chamber 145 in the housing portion 142. The axis of the housing portion chamber is disposed in the median plane of the grip member. The housing portion is planar at its end 146 and is internally threaded at 147 to receive a threaded sleeve 148 which forms a mounting end portion for the handle assembly.

The threaded sleeve 148 engages the inner transverse end 149 of a U-shaped support 150. This support 150 carries a pin 151 which supports the finger tip release push member 144. A spring 152 engages the push member 144 and the inner wall of the portion 145 to normally urge the push member 144 to protruding position.

The sleeve 148 engages the threads of the collar 79 so that when the handle is rotated the threads will cause the end 146 on the handle to approach the adjacent panel 84 of the door.

An escutcheon plate 153 is arranged about the member 142. This plate includes an internal flange 154 which is arranged beneath the face 146 and is engaged by a corrugated spring washer 155. The washer 155 is compressed as the handle is rotated thus clamping the escutcheon in place and holding the plate 76 in place to complete the assembly.

The sleeve 148 and the housing portion 142 have aligned apertures 156 and 157 through which the tip 158 of a spring 159 extends. This tip 158 prevents relative rotation between the parts 142 and 148. The tip 158 also is arranged in any one of a series of holes 160 in the escutcheon so that relative rotation between the escutcheon and the housing portion 142 is prevented.

The escutcheon includes a downwardly projecting tongue 161 which extends through aligned

holes 162 in the front panel of the door and in the plate 76 so that rotation of the escutcheon is prevented.

The tip 158 of the spring enters the hole 160 in the escutcheon when the threaded parts have been relatively advanced sufficiently whereupon the whole assembly will be held in place.

To release the handle the tip 158 of the spring is pushed inwardly until it frees the escutcheon whereupon the handle may be unscrewed.

The push member 144 includes a pin 163 which pivotally supports an actuating member 164. The actuating member 164 extends through a hole 165 in the end 149 of the member 150. The hole 165 is slightly larger than the actuating member (see Fig. 10) to permit the actuating member to swing slightly as the push member 144 reciprocates the actuating member. The free end of the actuating member 164 is offset from the pin 163 and is coaxially disposed with respect to the chamber 145 and sleeve 148. The inner end of the actuating member 164 is rounded as at 166 and fits within a groove 167 in the member 82.

After the parts are assembled pressure on the push member 144 will rock the member 82 thereby rotating the tube 71 and the rod 60, to move the arm 49 and thereby release the catch, as described in Patent 2,450,372 mentioned above.

The escutcheon holes 160 provide for adjustment of the handle position since by inserting the tip 158 of the spring in different holes different angle positions of the grip member 141 may be secured. Some people prefer a vertical arrangement of the inside handle while others prefer an inclined or a horizontal arrangement and the construction in a very simple manner provides for this desired adjustment. In releasing a latch the thumb of the hand grasping the grip member moves in an anatomically correct manner about its pivots in moving the push member to releasing position.

Having thus described my invention, I claim:

1. A handle assembly for operating an automotive vehicle door latch, said assembly including a housing body portion having an elongated grip member thereon, said housing body portion having a chamber therein, said housing body portion having an end portion thereon, said housing end portion being adapted to enter an aperture in a vehicle door, a supporting plate adapted to be disposed within a vehicle door, said plate having a hole adapted to be aligned with a vehicle door hole, said supporting plate hole receiving the housing end portion, the plate and housing end portion having interengaging portions whereby the plate is adapted to hold the handle assembly upon a vehicle door, said housing body portion having a hole therein adjacent to the grip member, said last mentioned hole opening into said chamber, a push member movably mounted within said chamber, said push member including an end portion having a pushing area permitting the thumb of a hand grasping the grip member to move about an axis perpendicular to the median plane of the grip member as the thumb sweeps across the push member in the act of moving the push member to latch releasing position, means normally urging said push member outwardly, a catch release actuating member, means to support one end portion of said actuating member in pivotal engagement with the push member, said supporting means including a transverse member in said chamber, said transverse member having a hole through which said

actuating member extends, the actuating member being free to move through said transverse member hole when the push member is operated.

2. A handle assembly for operating an automotive vehicle door latch, the assembly including a housing portion having a grip member thereon, the housing portion having a projecting end portion adapted to enter an aperture in a vehicle door, a pair of support plates adapted to be secured within a door, the support plates being spaced apart to receive the housing projecting end portion, the support plates and housing projecting end portion having opposed, coacting, converging, engaging portions which afford a camming action when the housing projecting end portion is moved inwardly, and means adapted to hold the handle assembly upon a door.

3. A handle assembly for operating an automotive vehicle door latch, the assembly including a housing body portion having an elongated grip member thereon, the housing body portion having a chamber therein, the housing body portion having an end portion thereon, the housing end portion being adapted to enter an aperture in a vehicle door, a plate having an apertured portion and adapted to be disposed within and to engage the inner surface of a vehicle door, the plate aperture being adapted to be aligned with a vehicle door hole, the plate aperture receiving the housing end portion, the plate and housing end portion having interengaging portions whereby the plate is adapted to hold the handle assembly upon a vehicle door, the housing body portion having a hole therein adjacent to the grip member, the last mentioned hole opening into the chamber, a push member movable within the chamber and having a portion projecting through the last mentioned hole, the push member including a catch release actuating member, and a transverse member carried by the housing, the transverse member having a hole through which the actuating member extends, the actuating member being free to move through the transverse member hole when the push member is operated.

4. A handle assembly for operating an automotive vehicle door latch, the assembly including a housing body portion having an elongated grip member thereon, the housing body portion having a chamber therein, the housing body portion having an end portion thereon, the housing end portion being adapted to enter an aperture in a vehicle door, a plate having an apertured portion adapted to be disposed within and to engage the inner surface of a vehicle door, the plate aperture being adapted to be aligned with a vehicle door hole, the plate aperture receiving the housing end portion, the plate and housing end portion having interengaging portions whereby the plate is adapted to hold the handle assembly upon a vehicle door, the housing body portion having a hole therein adjacent to the grip member, the last mentioned hole opening into the chamber, a push member movably mounted within the chamber, the push member including an end portion projecting through the last mentioned hole, a catch release actuating member, and means to support one end portion of the actuating member in pivotal engagement with the push member, the supporting means including a transverse member in the chamber, the transverse member having a hole through which the actuating member extends, the actuating member being

free to move through the transverse member hole when the push member is operated.

5. A unitary door handle assembly, the assembly including a housing portion having a chamber therein, the housing portion including a reduced tubular portion communicating with the housing chamber, the reduced tubular portion being adapted to enter an aperture in a vehicle door, there being a shoulder at the junction of the housing portion and reduced tubular portion, a washer on the reduced tubular portion and engaging the shoulder, the washer being adapted to engage the outer surface of a door, the shoulder limiting the inner movement of the reduced tubular portion, the reduced tubular portion having engaging means thereon adapted to coact with a companion member on a door to hold the handle assembly in place, an elongated grip member projecting from the housing portion, a push member movable in the chamber, a catch release actuating member, and means pivotally supporting the actuating member upon the support means for swinging movement and for reciprocation in the chamber, the support means including a transverse portion extending across the chamber, the transverse portion having a hole through which the actuating member extends, the last mentioned hole being larger than the portion of the actuating member which extends therethrough to permit the actuating member to have swinging movement as it reciprocates in the chamber, the actuating member having a portion engageable with an operating member to shift the operating member, the push member having a digit engaging portion accessible through the housing portion hole.

6. A handle assembly including an apertured housing portion having an end portion adapted to extend through a hole in a door, a handle projecting from the housing portion, a removable support in said housing, a push member on said support and disposed in the housing aperture, a removable transverse member carried by said housing, said transverse member having a hole therein, an elongated actuating member, one portion of the actuating member being slidable through the hole in said transverse member, means shiftable supporting the actuating member on said push member for reciprocation with, and for swinging on, the push member, the longitudinal axis of the actuating member intersecting the push member in all operating positions of the actuating member and the push member, and spring means urging said actuating member and push member in one direction.

7. For use in a latch construction which includes a pivoted operating member movable to release a bolt, a door handle assembly including a housing portion, an elongated grip member integral with, and projecting from, the housing portion, the housing portion having a chamber therein, one end of the housing portion having a hole therein, said hole opening into the chamber, a push member movable in the chamber and having a digit engaging end portion disposed in the hole, an elongated catch release actuating member, the catch release actuating member projecting outwardly beyond the other end of the housing, and pivotal mounting means pivotally supporting the catch release actuating member directly upon the push member so that the catch release actuating member advances with the push member and swings thereon, the longitudinal axis of the catch release actuating member intersecting the push member in all positions of the

two last mentioned members, the catch release actuating member having a portion engageable with a pivoted operating member and adapted to shift the operating member to bolt releasing position.

8. For use in a latch construction which includes a pivoted operating member movable to release a bolt, a bolt releasing assembly including a one piece housing portion, the housing portion having a chamber therein, one end of the housing portion having an opening leading into the chamber, a push member movable in the chamber and having a digit engaging end portion accessible through the opening, an elongated catch release actuating member, the catch release actuating member projecting outwardly beyond the other end of the housing, shiftable mounting means shiftable supporting the catch release actuating member upon the push member so that the catch release actuating member advances with the push member and shifts thereon, and a transverse member carried by the housing, the transverse member having a hole through which the catch release actuating member extends, the longitudinal axis of the catch release actuating member intersecting the push member in all positions of the catch release actuating member and the push member, the catch release actuating member having a portion engageable with a pivoted operating member and adapted to shift the operating member to bolt releasing position.

9. In a latch construction which includes a latch bolt, an operating member and means whereby movement of the operating member releases the bolt, a cylindrical housing, a grip member carried by the housing, said housing having internal threads therein, a collar adapted to be secured to a door, said collar having external threads engaging the housing threads, an escutcheon plate about said housing and adapted to engage the outer face of a door, means carried by the escutcheon plate adapted to prevent rotation of the escutcheon plate on a door, said escutcheon plate having an internal flange, a corrugated spring washer seated on said flange, the open end of said housing engaging said washer, said escutcheon plate having a series of circumferentially arranged apertures, said housing and said collar having aligned apertures, a spring disposed in said collar and having a radially directed tip extending through said collar and sleeve aligned apertures and having its extreme end adapted to be placed in any one of said escutcheon plate apertures to enable the angular position of the housing and grip member to be adjusted, an actuating member, a push member in said housing for operating the actuating member, the push member being accessible to a digit of a hand engaging the grip member, the actuating member being arranged substantially coaxial with and adjacent to the operating member and being operable to move the operating member to bolt releasing position in angularly adjusted positions of the housing and grip member.

10. For use in a latch construction which includes an operating member movable to release a bolt, a bolt releasing assembly including a housing portion having an inwardly open chamber, an elongated grip member projecting from the housing portion, the housing portion having a chamber therein and having an edge portion about the chamber which edge portion is adapted to engage the outer face of a door, one end of the housing portion including an extension which

is integral with the inner wall of the chamber and which projects from the housing beyond said edge portion and is adapted to extend through a hole in a door, the extension including a slotted 5 guide portion, the other end of the housing portion having an opening leading into the chamber, a push member movable in the chamber and having a digit engaging end portion accessible through the opening, the digit engaging end portion being accessible to a digit of the hand engaging the grip member, an elongated catch release actuating member, the catch release actuating member having an outer end projecting beyond the one end of the housing, and means supporting the catch release actuating member on the push member so that the catch release actuating member advances with the push member, the actuating member including an inner end portion disposed in and slidably in the slotted guide portion, the longitudinal axis of the catch release actuating member intersecting the push member at all times, the catch release actuating member having a portion engageable with an operating member and adapted to shift the operating member to bolt releasing position.

11. For use in a latch construction which includes an operating member movable to release a bolt, a bolt releasing handle assembly including a housing portion having an inwardly open chamber, an elongated grip member projecting from the housing portion, the housing portion having a chamber therein and having an edge portion about the chamber which edge portion is adapted to engage the outer face of a door, one end of the housing portion including an extension which projects beyond said edge portion and is adapted to extend through a hole in a door, the extension having engaging means thereon adapted to coact with a companion member on a door to hold the handle assembly in place, the extension including a slotted guide portion which is disposed adjacent to the inner end of the chamber, the other end of the housing portion having an opening leading into the chamber, a push member having a hollow end and movable in the chamber and having a digit engaging end portion accessible through the opening, the digit engaging end portion being accessible to a digit of the hand engaging the grip member, an elongated catch release actuating member, the catch release actuating member having an outer end projecting beyond the one end of the housing, and means supporting the catch release actuating member on the push member at a location within the push member so that the catch release actuating member advances with the push member, the catch release actuating member including an inner end portion disposed in and slidably in the slotted guide portion, the longitudinal axis of the catch release actuating member intersecting the push member at all times, the catch release actuating member having a portion engageable with an operating member and adapted to shift the operating member to bolt releasing position.
